UNITED STATES PATENT OFFICE.

WILLIAM NORRIS, OF PRESTON, ENGLAND, ASSIGNOR TO T. COULTHARD & COMPANY, LIMITED, OF PRESTON, ENGLAND.

VERTICAL TUBULAR BOILER.

SPECIFICATION forming part of Letters Patent No. 767,655, dated August 16, 1904.

Application filed July 12, 1902. Serial No. 115,267. (No model.)

To all whom it may concern:

Be it known that I, WILLIAM NORRIS, engineer, a subject of the King of Great Britain and Ireland, residing at Cooper Road, Preston, in the county of Lancaster, England, have invented certain new and useful Improvements 5 in Vertical Tubular Boilers and the Fittings for the Same, (for which I have made application for Letters Patent in Great Britain, No. 10 5,607, dated the 6th of March, 1902,) of which the following is a specification.

This invention relates to improvements in connection with tubulous boilers or steam-generators of the vertical type of construction, 15 the object being to provide such a form of feeding and a method of mounting the fire-bars within the boiler as will admit of a shell or cylindrical or other casing being employed wherein is no lower or usual opening for the 20 fire doors or grate and for feeding the fuel onto such fire-grate.

By means of my improved method of construction I am enabled to dispense with the usual fire-door in the lower drum or lower 25 portion of the boiler, and thus to secure a form of boiler of a more uniform and easily-produced type, such as will facilitate thorough inspection and which will minimize the 30 risks of leaky tubes due to the present unequal temperatures acting upon such tubes where openings for fire-doors are in use upon the ordinary types of vertical fire-tube boilers.

In the accompanying drawings, Figures 1 and 2 are sectional elevation and sectional plan 35 of one form of boiler constructed according to my invention.

In carrying my invention into effect when constructing a vertical boiler suitable for motor-car use or for other steam-generation purposes I provide a shell or outer casing *a*, in which no opening is made for feeding the fire-grate; but I instead form a central feeding-tube *b*, which passes through the water-space from the fire-box *c* to the smoke-box end of 45 the shell, and on or about the upper or outer end of this tube I arrange a hopper or feeding-receptacle *d* for supplying such tube or

fire-chamber connection with fuel. The tube is fitted with a removable plug or stopper *b'*.

I prefer to make the smoke-box *e* of my 50 boiler in the form of a circular hood-like cover to the boiler into which the upper ends of the fire-tubes may open, while the central or enlarged feeding-tube *b* I carry through this hood. I make the outer surface of the hood 55 or cover to form the receptacle or hopper *d* for fuel-supply, and for this purpose I prefer to make the surface of the cover sloping or conical. The uptake or chimney *f* I secure to one portion of the hood or to the 60 side of boiler-shell, as may be most convenient. By this arrangement of central firing I insure that the fuel shall be delivered onto the center of the fire-grate *g*, and I am also enabled to carry the water-jacket or lower 65 portion *h* of the boiler entirely and uninterruptedly around the fire-box *c*. The fire bars or grates *g* I prefer to mount upon pivots *p* or hinge-like carriers, so that when they need cleaning or clinkering they can be readily 70 swung down or lowered by handles, such as *n*, into a position where they can be operated upon from the lower ash-pit or damper doors arranged at the lower end of the shell of the boiler. I find it convenient to form these 75 ash-pit doors as inclined members *i*, with inner hinges or pivots *k*, which admit of the doors being moved into an open position, when the hinged fire-bars *g* may be able to fall for discharging their ashes or for cleaning or examination purposes.

The damper-frame *l* I attach to the ash-pit, providing ordinary connections and means for regulating the damper to suit any requirement for steam-producing purposes. 80

The base of the boiler I modify to suit the position or frame upon which it is to be mounted, and the method of constructing the shell I also vary to suit the sizes of plates that are necessary for the particular type of boiler 90 which is to be constructed.

I do not limit the application of my invention to any special arrangement of vertical hopper or to any particular method of mount-

ing the movable fire grate or bars within the lower portion of the boiler or its fire-box; but I modify the system of construction to suit the size of boiler that is to be produced and the 5 position on which it is to be employed.

Having now particularly described my invention, what I claim as new, and desire to secure by Letters Patent, is—

1. In a vertical tubular boiler having a 10 shell with no fire-door opening and a central feeding-tube passing from the fire-box to the smoke-box end of the shell, the combination of a grate consisting of two flat semicircular grates *g* hinged on their diameters and pro- 15 vided at their circumferential edges with han- dles *n* for lowering the grates at the said edges for clinkering purposes, substantially as hereinbefore described.

2. In a steam-boiler, in combination, a shell

or casing having its vertical walls continuous, 20 that is without a fire-door opening therein, a central feeding-tube passing through the water-space from the fire-box to the smoke- 25 box end of the shell, a smoke-box having a depressed top forming a hopper leading to the tube, a grate consisting of two semicircular grates hinged on their diameters, and an ash- 30 pit inclosing the lower part of the shell below the grate and provided with hinged doors and a damper substantially as hereinbefore described.

In witness whereof I have hereunto set my hand in presence of two witnesses.

WILLIAM NORRIS
